INVENTOR

JACOB SUTER

BY *Franklin J. Foster*

ATTORNEY

UNITED STATES PATENT OFFICE.

JACOB SUTER, OF WEST NEW YORK, NEW JERSEY.

WINDOW CONSTRUCTION.

Application filed March 18, 1927. Serial No. 176,506.

The present invention is concerned with the provision of a window construction of substantially conventional appearance in which two sliding sashes are mounted in a window frame, either or both of the sashes being capable of inward swinging movement in order that their outer surfaces may be readily cleaned without danger of a cleaner falling out of the window.

- 10 It is an object of the invention to provide a window embodying this feature of construction, while retaining substantially the conventional appearance of an ordinary window, and involving a minimum number 15 of structural changes in the ordinary window. In fact, any conventional type of sliding sash may be readily converted in accordance with the present invention in a short time, and with slight labor.
- 20 Other objects of the invention are to provide a window of simple, practical construction which will be rugged, durable and efficient in use, in which the sashes are readily manipulable into inwardly swung 25 position for cleaning purposes, and may be readily sustained in operative inwardly swung position for cleaning.

With the above noted and other objects in view, the invention consists in certain novel 30 features of construction and combinations and arrangements of parts, as will be more fully hereinafter set forth and pointed out in the claims. The invention may be more 35 fully understood from the following description in connection with the accompanying drawings, wherein—

Fig. 1 is a vertical sectional view through a window embodying the present invention.

Fig. 2 is a similar view showing the 40 sashes swung inwardly and held in proper position for cleaning.

Fig. 3 is a fragmentary front elevational view showing one of the upper corners of the lower sash.

Fig. 4 is a similar view showing one of the 45 lower corners of the upper sash.

Fig. 5 is a longitudinal sectional view through a modified type of window.

Fig. 6 is a view similar to Fig. 5, but 50 showing the sashes swung inwardly.

Fig. 7 is a detail, front elevational view, showing one of the adjustable sash supporting bars attached to the inside face of the window frame.

55 Referring first to Figs. 1 to 4 of the drawings, I have shown a window frame 10 in

which are slidably mounted the usual outer upper sash 11 and lower sash 12. The sliding movement of these sashes may be guided by the outer weather strip 13, inner moulding strip 14 and central parting strip 15. Sash cords 16 of conventional construction are employed, or the lower ends of the sash cords may be made of wire 17 if desired, so that the cords will not interfere with the inward swinging movement of the two sashes when the lower sections 14^a and 15^a of the moulding strips and parting strips respectively are removed. The top of the upper sash is cut away as indicated in dotted lines at 11^a so that it will not gain on the sash cord as the sash is swung inwardly.

Carried by the upper corners of the lower sash 12 are bolts 18 sliding in sleeves 19 and operated by handles 20, these bolts 75 adapted to be projected into any of a series of socket members 21 in the window frame when the lower sash is slightly lifted to clear the sill 22 and align the bolts with the sockets. With the lower section of the 80 moulding strip removed, the lower sash 15 may be swung inwardly and upwardly about the bolts 19 as pivots and latch in its inwardly and upwardly swung position in any approved manner as for instance by the 85 flexible devices 23 anchored to the window frames and engaging hooks 24 mounted on the sash.

A substantially similar construction is used at the under corners of the upper sash, 90 except that in this instance the bolts 25 are formed with eye portions 26 projected into engagement with studs 27 extending inwardly from the window frames. Bolts 25 slide in guides or sleeves 28 and are operated 95 by handles 29. The upper sliding sash may be swung inwardly and downwardly about the studs 27 as pivots and hung in this position by flexible devices 30. Without removing the strip sections the lower sash may be 100 slightly lifted and locked by its bolts, providing ventilation without danger of a child tumbling through the partially opened window.

In Figs. 5, 6 and 7 I have illustrated a 105 modification of the invention in which the use of the pivot bolts is eliminated, and both of the sashes capable of inward and upward swinging movement. Different means is used for supporting the sashes in their inwardly swung position, and mechanism is 110 shown for latching the removable moulding

strip sections 14^a to the stationary sections 14.

In this form of the invention, bolts 31 guided within sleeves 32 fixed to the upper 5 moulding strip sections 14 have limited movement due to the presence of a pin 33 passing through slots (not shown) in the bolts. The ends of the bolts are adapted to be projected downwardly into keeper members 34 carried by the lower removable moulding strip sections 14^a.

In this form of the invention with the lower sections of the moulding strips and parting strips removed, the two sashes 11 15 and 12 may be swung upwardly and inwardly together, or individually, and retained in this position by the use of inwardly swinging levers 35 pivoted as at 36 to the outer face of the window frames or to a 20 wall adjacent the frames and carrying locking members 37 adapted to work in any of a series of holes 38 in the window frames or wall. Coacting with the levers 35 are swinging levers 39 pivoted to the outer portions 25 of the window frames and adapted to be swung to the position of Fig. 6 where they engage under the keeper members 34. The two sashes when moved to the position of Fig. 6 are thus locked against accidental 30 downward swinging movement by the cooperative action of bars 39 and levers 35. With this form of the invention, conventional sash cords may be used. Obviously, the bolts and keepers for removably connecting 35 the two sections of the moulding strips might be used with the construction of Figs. 1 and 2, although I have not illustrated them in connection with this form of the invention; also chains 50 may be utilized if de- 40 sired.

Various changes and alterations might be made in the general form and arrangement of the parts described without departing from the invention. Hence I do not wish to limit myself to the details set forth, but 45 I shall consider myself at liberty to make such changes and alterations as fairly fall within the spirit and scope of the appended claims.

I claim:

1. A window including a frame, upper and lower sliding sashes therein, parting strips and moulding strips guiding the sliding movement of the sashes and including lower removable sections to permit the 55 sashes to be swung inwardly, means for holding the sashes in inwardly and upwardly swung position when the lower strip sections are removed, including levers pivoted to the inner face of the frame and 60 swinging inwardly under the upwardly swung sashes in planes parallel to the planes of sliding movement of the sashes.

2. A window including a frame, upper and lower sliding sashes therein, parting strips and moulding strips guiding the sliding movement of the sashes and including lower removable sections to permit the 65 sashes to be swung inwardly, means for holding the sashes in inwardly and upwardly swung position when the lower strip sections are removed, including levers pivoted to the inner face of the frame and 70 swinging inwardly under the upwardly swung sashes, and levers pivoted to the outer 75 portions of the frame and swingable inwardly and upwardly to overlie the outer ends of the inwardly swung sashes.

JACOB SUTER.
